UNITED STATES PATENT OFFICE.

CHARLES DENNISTON BURNETT, OF ALRESFORD, ENGLAND.

APPARATUS FOR OFFENSE OR DEFENSE AGAINST SUBMERGED OR PARTIALLY SUBMERGED OBSTRUCTIONS.

1,400,211.

Specification of Letters Patent.

Patented Dec. 13, 1921.

Application filed September 18, 1917. Serial No. 192,018.

(GRANTED UNDER THE PROVISIONS OF THE ACT OF MARCH 3, 1921, 41 STAT. L., 1313.)

To all whom it may concern:

Be it known that I, CHARLES DENNISTON BURNETT, a subject of the King of Great Britain, residing at Dean Holme, Kilmes-ton, Alresford, in the county of Hants, England, have invented certain new and useful Improvements in Apparatus for Offense or Defense Against Submerged or Partially Submerged Obstructions, (for which I have 5 filed application for Letters Patent of Great Britain June first, 1915, Patent No. 8,117,) of which the following is a specification.

Hitherto various devices have been suggested or employed for use against submarine vessels or mines. For attacking submerged submarines charged bodies or sweeps have been towed from the attacking vessels, the charges being fired when the 10 body or towing cable of the same is in contact with the submarine, or the charge is thought to be in the vicinity of the same. The results obtained from the use of such sweeps, however, have not been so successful as is desirable. For protecting ships 15 against mines, various forms of water kites have been employed but the protection so afforded has not been altogether satisfactory.

My invention relates to apparatus for use as a weapon of offense or defense against submerged or partly submerged vessels, or obstructions such as submarine mines, and has for its object the provision of a new or 20 improved form of apparatus which fulfills in a more efficient manner the requirements which have now arisen with the latest developments of naval warfare.

My invention consists in an apparatus so 25 constructed that when towed from a point which may be above, below, or on the surface of a fluid, or when moored in a fluid having a translational movement, the apparatus will, as a whole, take a predetermined angle from the vertical, and will keep such predetermined angle at all speeds of the apparatus and fluid relatively to each other within predetermined limits.

My invention further consists in providing such an apparatus with means whereby it can be used to damage or destroy sub-

merged or partly submerged vessels or obstructions.

My invention further consists in providing such an apparatus with means whereby it can be used as a moored mine, particularly for use in tide-ways.

My invention further consists in modifying or adapting such an apparatus so as to be applicable as a mine-sweeping device for ships whereby mines in the path of the ship are swept aside and are prevented from making contact with the hull of the ship which would cause the explosion of the mines, the mine-sweeping apparatus being provided or not as desired with means whereby the mines can be detached from their moorings or destroyed or otherwise treated so as to render them innocuous, with means for indicating in any suitable place on the ship when the apparatus is in engagement with the mine, and also if the mine is being carried along by the apparatus, and with means for keeping the point of attachment of any towing member to the ship away from the hull at a desired distance which is particularly desirable for the towing members at the bow.

My invention further consists in an apparatus which will tow out from the fore and aft line of a ship and which may be combined with an apparatus as referred to above whereby the latter apparatus is made to travel at a greater horizontal distance away from the fore and aft line of the towing vessel, or may be used to support a suitable protecting means against torpedo attack.

My invention further consists in a sweeping device for use against submarines, and which can be supplied as a self-contained unit or units to ships thereby to form a permanent or temporary addition to their armament.

My invention further consists of a system of firing for use with towed charges whereby the charge can be fired in any one of three ways: (1) Automatically by direct impact upon a resisting object such as a submerged submarine; (2) automatically by the tension in the towing cable or like member exceeding a predetermined amount, due to

an obstruction to the passage of the towed charge being met with; (3) at any moment the charge is in the water at the will of the control officer.

5 My invention further consists in an improved form of dynamometer firing gear for use with towed charges.

10 My invention further consists in an improved means for insuring that the detonators for high explosives commonly used in submarine weapons are automatically inserted in the firing position on the weapon entering the water, but which when the weapon is leaving the water effects the displacement of the detonators from the firing position.

15 My invention further consists in an improved depth recorder for use in towed charges.

20 My invention further consists in a winch specially suited for use with towed charges.

25 My invention further consists in an improved construction of dropping-davit which is applicable generally for lowering or raising charged bodies.

30 My invention further consists in the details of construction and in the arrangement and operation of the parts hereinafter described.

35 Before describing the constructional details of the apparatus embodying my invention, certain basic principles underlying and governing such apparatus will now be discussed with reference to Figures 1 to 13 of the accompanying drawings in which:—Fig. 1 is a diagrammatic view showing the forces brought into operation when a body according to this invention is towed by a vessel.

40 Fig. 2 is a view illustrating how, with a given towing wire, the depth at which the body travels depends upon the construction and arrangement of the body.

45 Figs. 3 and 4 illustrate bodies with depressing planes but with the parts symmetrically and asymmetrically arranged.

50 Figs. 5 and 6 illustrate how with bodies as shown in Figs. 3 and 4 the buoyancy couple of the body may be considered as a weight below the axis of the body.

55 Figs. 7, 9 and 10 illustrate bodies with the weights of the shaded parts arranged in different ways.

58 Figs. 8 and 11 illustrate bodies with an asymmetrical plane, and a light tail respectively.

60 Fig. 12 illustrates a towed body provided with a plane with the point of tow not passing through the center of pressure of the plane, and

65 Fig. 13 illustrates the forces called into play when towing a body provided with planes, and adapted to run on the surface of the water.

68 Fig. 14 is a diagrammatic view looking 35 toward the stern of the vessel fitted with a

stern and beam apparatus applicable for sweeping for submarines.

Fig. 15 is a birdseye view of the same.

70 Fig. 16 is a similar view to Fig. 15 but on a larger scale showing the use of the stern sweep only, and the position of the winches, and the dropping davits with the charged torpedo held therein. The above three figures are for illustration purposes only and are not for showing any constructional details.

75 Figs. 17 and 17^A show the general arrangement of a charged torpedo according to my invention.

80 Fig. 18 shows on a larger scale the head of the charged torpedo laid open, and certain features in detail.

85 Figs. 19 and 20 are respectively part section and plan views showing the method of carrying and ballasting the depressing plane.

90 Figs. 21 and 22 are part sectional elevation and plan of the body and tail of the charge torpedo.

95 Figs. 23 and 24 are sectional elevation and plan views of the depth indicating apparatus for towed bodies.

98 Figs. 25 and 26 are front and side elevation of the bonnet of the charged torpedo, and part of the firing gear.

100 Figs. 27 and 28 are the side and front elevation of the detonator withdrawing and inserting gear.

105 Fig. 29 is a horizontal section of a casing for the detonators adapted to keep the primer or like explosive watertight.

110 Fig. 30 is a plan view of a spare detonator carrier in a suitable box.

115 Fig. 31 is a view showing the general arrangement of the winch, according to my invention.

120 Figs. 32 and 33, are views showing the details of a pawl disengaging gear for the winch.

125 Fig. 34 is an elevation of the dynamometer gear carried by the winch.

130 Figs. 35, 36 and 37 are views of an indicator gear to register the amount of wire veered from the winch.

135 Fig. 38 is an elevation showing the general arrangement of the dropping davit according to my invention.

140 Figs. 39, 40 and 41 are detailed views of the dropping gear for the davit, such details being employed in naval service davits 120 for torpedoes, and forming no part of this invention.

145 Fig. 42 is a diagrammatic view of the firing switchboard mounted in a convenient part of the ship such as the forebridge.

150 Fig. 43 is an elevation of the interior of a push for an ammeter.

155 Fig. 44 is a top plan view thereof with the cover removed.

160 Figs. 45 and 46 are side elevation and

front elevation with the cover removed of a firing switch.

Figs. 47 and 48 are side and front elevation of a safety switch.

5 Fig. 49 is a view of a one pin plug socket.

Figs. 50 and 51 are side and front elevation of the dynamometer switch.

10 Figs. 52 and 53 are two views at right angles showing the arrangement of the winch contacts.

Fig. 54 is a diagram of connections.

15 Figs. 55 and 56 are views showing the method of connecting the electric towing cable.

Figs. 57, 58 and 59 are respectively front and end elevations and plan view of the form of surface torpedo according to my invention.

20 Figs. 60 and 61 are front and end elevations of another form of surface torpedo.

25 Figs. 62 and 63 are diagrammatic views illustrating the use of my invention for mine protection or mine sweeping.

Figs. 64 and 65 are plan and part vertical section of one form of body used for this purpose.

30 Figs. 66 and 67 are end elevations looking toward the nose and tail of this torpedo respectively.

In order that an apparatus should fulfil efficiently practical requirements it is essential that it should keep at a constant depth for any variation of speed and alteration of course, these requirements not being met with in the forms of "sweeps" and "kites" hitherto employed or suggested.

35 In all towed bodies provided with hydrovanes, planes or like surfaces, the depth 40 which the body will reach depends upon the depressing power of the plane on the one hand, and on the total drag or resistance to movement in the direction of motion on the other hand.

45 Consider the case of a body provided with a depressing plane and towed from a ship so that the direction of motion is along the line OP Fig. 1 which is parallel to the fore and aft line of the ship and vertically beneath it.

50 The resultant dynamic reaction on the depressing plane is say in the direction shown by the arrow "A." This re-action can be resolved into two components B and C respectively at right angles to the line OP and 55 along or parallel to the line OP. There is also the resistance or drag D of the body to movement in the direction OP. Neglecting for the time being the effect of a towing member, the force parallel to the direction

60 of motion is C+D. The forces at right angles to and along the direction of motion are known respectively as "lift" and "drag" or "drift," it being observed that with a depressing plane the "lift" is in a negative or 65 downward direction.

In the above example therefore the lift/drift ratio will be $\frac{B}{C+D}$ and the angle which the towing member will take up relatively to the body when in a position of equilibrium will depend upon this lift/drift ratio alone.

Considering now the force on the towing member due to its movement through the water and taking any unit section, the reaction for this section will be normal to it. This force can be resolved into the two components G and H respectively at right angles to the direction of motion and along it. Let G and H be the resultants of these two sets of components for the whole length of the towing member. The total lift will therefore be the algebraic sum of the forces B+G and the total drift will be the algebraic sum of the forces C+D+H. In this case the lift/drift ratio will be $\frac{B+G}{C+D+H}$ and the angle of the towing member to the body will depend upon this ratio.

It will be evident that the value of the lift/drift ratio of the body as a whole and consequently the angle of the towing member to the body depends upon two sets of quantities, each set capable of varying independently.

95 Therefore, with any given towing member the lift/drift ratio and the angle referred to above will depend upon the construction and disposition of the parts and weights of the body, while, with a given body the lift/drift ratio will depend upon the dimensions of the towing member. With a given towing member the angle will be a maximum when the lift/drift ratio has a maximum value, so that the maximum depth to 100 which a body will run or tend to run when towed under normal conditions will depend upon the maximum value of this lift/drift ratio.

105 The lift/drift ratio is governed chiefly by the characteristics of the body as a whole. The lift/drift ratio of the depressing plane will depend upon its physical characteristics such as length of the plane, length of the chord of the transverse section of the same, 110 the contour of the plane and the angle of incidence. It is obvious that the ratio of the length of the plane to the length of the chord of the transverse section which ratio is known as the aspect ratio, will largely govern the efficiency of the plane, and there is 115 always a maximum practical value of this aspect ratio governed by considerations of weight and strength.

120 The drift of a body is at a minimum when it is of a stream-line form such as torpedo shaped.

125 It is therefore clear that the lift/drift ratio of the body has its practical maximum value when it is constructed of stream-line 130

form or torpedo shaped and it is provided with planes of the best practical aspect ratio.

A body will therefore tow at the maximum depth when it is constructed on the above principles and any departure from this construction will lessen the depth, such as for instance a body consisting of a flat body weighted eccentrically will run very shallow.

Fig. 2 shows diagrammatically the maximum depths D^1 , D^2 , D^3 , to which the bodies B^1 , B^2 , B^3 , of lift/drift ratios respectively 4, 6 and 8, will run when towed by a given member, and also shows why with a given member and a lift/drift ratio of a body there is a certain maximum depth which it is not possible to exceed however much the length of towing wire is increased.

The lifting effect of a towing member such as a wire varies directly as $d^{1.8}$ to $d^{1.9}$ where d is the diameter with the addition of a small correction for the surface friction dependent upon the type of wire used. At the same time the strength of the wire varies as the cross-sectional area. It is possible therefore with any lift/drift ratio of body to increase the depth by increasing the weight and keeping the size of the wire constant, or decrease the size of the towing wire and keep the weight of the body constant.

It will be seen therefore that the maximum speed at which it is required to tow the body determines the maximum depth at which it is possible to be run. By using best high tensile steel and a body of high lift/drift ratio, it is possible to reach a depth of 100 feet at 30 knots and still keep a good factor of safety on the wire.

As an example of the variation in depth caused by altering the size of the towing wire a body when towed by a $1\frac{1}{4}$ " wire ran at a depth of 53 feet, while with a 2" wire it ran at a depth of 42 feet, in each case there being 72 feet of wire in the water and the body running with the towing in the vertical plane through the fore and aft line of the ship.

It has been assumed so far that the body was running in a vertical plane passing through the fore and aft line of the ship.

The case will now be considered where the body runs at an angle to this plane, that is at a distance laterally with respect to the fore and aft line.

Figs. 3 and 4 illustrate a body Y provided with a depressing plane X the whole being symmetrically arranged in Fig. 3, but the plane in Fig. 4 being weighted at one end.

In Fig. 3 as shown the body will float when free with the plane X horizontal and on the body traveling through the water it is evident that in view of the symmetrical arrangement, the resultant dynamic reaction on the plane which equals $K A V^2$, (where K is a constant, A is the area of the plane, and V is the velocity) the downward force due to the weight of the body W, and the

upward force W' , due to the buoyancy are all in the same line so that the resultant force is along the vertical line of symmetry.

With the example illustrated in Fig. 4 however the body when floating statically would take up a position of equilibrium as shown, with the plane at an angle to the horizontal due to the weight on one end of the plane. When towed through the water the resultant dynamic reaction $K A V^2$, will be normal to the plane, and will be at an angle to the vertical line along which act the forces due to the weight and buoyancy, and the body will run at this angle in the condition of equilibrium.

If the body and plane are truly symmetrical the body will run at this angle for all speeds as should it tend to take up a different position the buoyancy couple will restore it to its original position. This buoyancy couple can be considered as a weight W^2 , concentrated at a distance below the axis of the body as shown in Figs. 5 and 6, and will be hereinafter referred to as the rotary stability couple. In bodies accord-

ing to my invention, which will be herein-after referred to as the Burney torpedo, or the charge torpedo, the weights of the component parts such as the charge of explosive, detonator gear for same, and depth-indicating gear are arranged low down with respect to the axis so that the rotary stability couple has a considerable value in order to right the body speedily should any change take place in the equilibrium position. The Burney torpedoes are made in three main parts, the head, the body and the tail, and as any torpedo is used for starboard or port running, arrangements are made always to keep these weights low. This is effected by making a head and tail in such a way that they can be put on the body at any angle and remain in the same plane with each other.

Fig. 7 shows how the Burney torpedo is arranged to keep the weights low, the shaded portions being able to rotate to be adjustable.

If these torpedoes were made absolutely symmetrical no adjustment would be necessary, but this is never the case in practice so a permanent adjustment is required on the rudder at the tail.

The effect will now be considered with reference to Fig. 8, if the depressing plane is not symmetrically disposed with respect to the torpedo. Suppose for instance it was $\frac{1}{2}$ inch longer at the point B than at A. At 20 knots the total force on a 3 foot 6 inches length of plane which is the useful length of a plane of 4 foot 6 inches length, is 1640 lbs., therefore on $\frac{1}{2}$ inch it is 1.22 lbs. At 29 knots the force is 3550 lbs., on the plane and on $\frac{1}{2}$ inch is 2.04 lbs. The length of the plane being 4 feet 6 inches this force is acting 27 inches from the center, consequently at 20 knots the upsetting mo-

ment is 33 inch-lbs., and at 29 knots 72 inch-lbs.

Suppose the rotary stability or buoyancy couple is 700 inch-lbs., with the torpedo illustrated in this figure, at 20 knots the torpedo 5 will be running inclined at an angle, 70

$$\tan^{-1} \frac{1.65}{35} \text{ or } 2^{\circ}42', \text{ and at 29 knots}$$

10 $\tan^{-1} \frac{3.6}{35} \text{ or } 7^{\circ}.$

If the torpedo was running normally at an angle of 50 degrees to the vertical axis of symmetry of the torpedo and at a depth of 15 60 feet, the error in depth caused by this fault in the setting of the plane would be about 11 feet at 29 knots. If this torpedo 20 was running on the port side this error in plane setting will tend to make it run shallow.

If the rudder is put over to starboard it will tend to steer the torpedo into starboard or near the ship and the position of the 25 towing wire will take up a resultant position as shown by the arrow R.

The point of application of the towing member is on the outside of the torpedo body and the force can be resolved into horizontal and vertical components, the horizontal component C of which will act to rotate the torpedo against the plane. As both force on the plane and on the rudder vary as the square of the velocity this error can be corrected at all speeds. A rough and ready rule 30 to apply is:—if the torpedo runs shallow steer it into the ship and if deep away from the ship.

In addition to the rotary stability couple 40 there is a fore and aft buoyancy couple on the torpedo which is hereinafter referred to as the longitudinal buoyancy couple.

Consider a torpedo designed as in Fig. 9 in which all the weight is in the head. The 45 tail will run high so that the center of gravity is low compared with the center of buoyancy and therefore the rotary buoyancy couple will be increased.

With a torpedo designed as in Fig. 10 to 50 float horizontally so that the weight of the after part balances that of the head and plane, the rotary buoyancy couple will be reduced. Consequently with a torpedo running straight it is advantageous to have a light tail in order to have a large rotary 55 stability couple. Should, however, the torpedo be running at an angle a further complication is introduced. Fig. 11 shows an end-on view of a tail which is light. If running straight the buoyancy of the tail acts 60 vertically as shown by the arrow B.

Suppose, however, the torpedo is ballasted 65 with a weighted starboard so that it runs out to port, the tail will rotate through an angle in the direction of the arrow "A." The buoyancy of the tail will still be acting ver-

tically, and it can be resolved at right angle to the rudder and the elevating planes, the components being represented by the arrows R and E. In this case, the effect of the light tail has been to put starboard rudder on and 70 the torpedo will consequently tend to run deep. This could be corrected by putting port rudder on, but only at one speed, because the rudder correction varies as the square of the velocity, and the buoyancy is 75 constant. The result of such an attempt to correct this error will be to under-correct at a low speed and over-correct at a high speed. Consequently with the torpedoes 80 running at an angle advantage cannot be taken of a light tail to increase the rotary stability or buoyancy couple.

From the results obtained by using light and heavy tails on a torpedo running at an angle and correcting the same, it is shown 85 to be preferable to have the tail at the most 2 or 3 lbs., on the light side, rather than have the tail on the heavy side, as the variation in depth in the former case over a wide range of speed is appreciable.

The position of the point of tow and the depressing plane will now be considered.

The position of the center of pressure of the water on the torpedo is the determining factor for the point of tow. At small angles 90 of inclination the center of pressure is very far forward and if the point of tow was above this center of pressure, severe oscillations would set in, and if sufficiently far aft the torpedo would tend to tow broadside and 95 come up. The position can be given a wider margin by fitting vertical fins or planes aft, this having the effect of throwing the resultant centers of pressure aft.

In the present design of Burney torpedoes 100 the position of the depressing plane is so chosen that the line of action of the tow passes through the center of pressure on the plane. If this were not the case, the condition shown in Fig. 12 would result, and a 105 couple would be set up making the tail depress until the lifting effect of the horizontal fin is sufficient to balance it. The effect would be that the angle of incidence of the plane and torpedo would be reduced, 110 consequently the down force would be reduced, and the resistance, or drift, or drag would be increased, as the horizontal fin would be working against the depressing plane. The net result would be to decrease 115 the lift/drift ratio of the torpedo as a whole, thereby reducing the depth at which the 120 torpedo runs.

As hereinbefore referred to, the Burney 125 torpedo may be suspended from a body arranged to tow substantially on the surface of the water and laterally outward from the ship. This body will hereinafter be referred to as the surface torpedo. The action of a surface torpedo is considerably more compli- 130

cated than in the case of the Burney or charge torpedo, owing to the former being sometimes wholly and sometimes partially immersed.

- 5 Fig. 13 gives a diagrammatic representation of the forces acting on the system where the surface torpedo is employed, P being the pull of the tow-rope S , the outward thrust of the surface torpedo and T the drag of the charge torpedo. The drag of the charge torpedo at different speeds can be ascertained by towing with a dynamometer and registering the strain so that if the angle θ to the fore and aft line of the ship is fixed at a 10 certain minimum say 40 degrees, it becomes possible to calculate the value required for the outward thrust S at any given speed. In the same way as the plane on the charge torpedo keeps it down, so planes can be 15 provided for the surface torpedo to keep it out. In addition to the drag of the charge torpedo and its wire, by which it is towed, the resistance of both surface torpedo and its planes must be calculated and added. 20 As the actual operation of the surface torpedo will depend very largely on its construction this point will be more fully explained when the construction of the surface torpedo is hereinafter mentioned and 25 described.

According to my invention a body having the property of towing steadily under water at a predetermined angle to the vertical and at a predetermined depth is constructed from 30 any suitable material and is provided with a one or more hydrovanes or planes in such a way that the downward thrust of the depressing plane or planes is balanced by the pull of the towing cable or the like, and with 35 a tail fitted with a plane surface which may be adjustable, so arranged that its action in conjunction with the main depressing plane or planes gives stability in longitudinal direction. The disposition of the parts and 40 45 the weights of the body are so arranged to give stability against any rotational movement. The point of tow on the body is situated well forward and the tail plane is so arranged that lateral oscillation is damped out.

50 The angle at which the body tows from the vertical is governed by the direction of the resultant dynamic reaction as hereinbefore described and is maintained by the buoyancy couple, and the depth at which the body will 55 run is governed by the lift/drift value of the same.

A body according to my invention in its most efficient form which would tow at a largest practical angle to the vertical and at 60 a maximum depth, is constructed of stream line form, and is provided with one or more depressing planes of the best practical aspect-ratio and efficient sectional form, so that the lift/drift ratio of the body as a 65 whole is practically maximum, and the dis-

position of the parts and weights are so arranged that the line of tow passes through the center of dynamic reaction on the component parts of the body.

This method of design and construction is 70 equally applicable to a condition in which the body is relatively stationary or moored and the water moving. That is to say this construction provides for an improved form of submarine mines, particularly for use in 75 a tideway. In this case, the buoyancy couple will be so arranged in conjunction with the setting of the main plane or planes, that the resultant forces acting on the body viz.— the weight, the buoyancy, and the dynamic 80 reaction caused by the travel of the water past the mine, will be in an upward direction, whereby the disadvantage common to mines of the construction hitherto used of being depressed when moored in a tideway 85 is overcome.

A towed body constructed as above described may be provided with a charge of high explosive and with means for firing same, in which case it can be used as a sweep 90 against submarines, or the body may be uncharged, and used for mine sweeping operations, or for protecting ships against mines, in which case one or more pairs of such bodies are towed from points in a ship arranged below or above or on the water-line, but preferably from points well below the water line, so that all mines are swept aside, so that it becomes impossible for a mine to come into contact with the side of the ship, 100 the disposition of the bodies and towing cables being so arranged as to prevent a mine slipping in between any gaps and so come into contact with the side of the ship.

If desired, the towing cable may be fitted 105 with any suitable form of anti-sweeping device or "gate" whereby the mooring rope of a mine is caused to pass the device in any of the well-known ways, so that each towing cable in turn can meet and pass the mooring 110 115 of the mine, and at the same time cause it to be swept away from the side of the ship.

Also the towing cable can be fitted, if desired with any suitable form of cutters in order to sever the mooring rope of the mine 115 whereupon the latter would rise to the surface where it could be destroyed or rendered innocuous in any suitable way.

Or, if preferred, small explosive charges 120 may be provided on the mine-sweeping device, which, when fired, will cause the destruction of the mine.

Further, if desired, each towing cable may be provided with means to indicate when a mine or mooring of the same has become engaged, and if the sweep is carrying the same along. For this purpose, each towing cable may be connected to a piston inclosed in a cylinder containing a liquid such as water 125 which is in communication with a pressure 130

gage mounted in any convenient position on the ship.

When a cable of the sweeping device meets an obstruction the piston is operated to work the pressure gage. When the obstruction gets clear of the cable, the indicator of the pressure gage returns to its normal position, but should the towing cable carry the obstruction along with it, or not be able to 10 clear the same, the indicator of the corresponding pressure gage will register this fact, whereupon any desired steps may be taken to get rid of the obstruction.

Further, if desired the inner ends of the 15 towing cables at the bows or any desired position may be guided through submerged tubes projecting outward, or be attached to a rod, bar or like member arranged to project outward from the side of the ship, such 20 members being rigidly or adjustably secured to the ship in any suitable way. A preferred means is that in which the adjustable member is in the form of a plunger working in a cylinder and can be withdrawn within 25 the hull or pushed out into position at will. By this means, the point of tow at the ship is such that the towing cables at their inner ends can be kept well out from the ship's hull.

30 It is evident that by arranging a plurality, of such mine sweeping devices on both sides of a ship, it becomes possible for even the largest battleship to traverse mined water, but be safely protected without unduly diminishing its speed, such protection if desired being placed in position only when a ship enters a mined area.

By arranging the points on the ship from which the bodies are towed to be well below 40 the water-line the bodies are made to tow out in nearly a horizontal direction so that dynamic reaction on the body is used to the maximum advantage to keep the said body at the greatest horizontal distance from the 45 ship. In some cases it may be considered more important to provide a body of a cheap and suitable construction which can be readily made up, but which will tow only at a small pre-determined angle from the vertical. 50 cal, rather than of a more costly and intricate construction which will tow at a large or maximum angle from the vertical. In such a case the body may consist substantially of a flat surface such as a plate, board 55 or the like, provided with a suitable weight arranged low down with respect to the surface and to one side of the same.

In order to increase the horizontal displacement of the towed bodies above described, from the side of the ship, they may be suspended from a float or buoy herein-after referred to as a surface torpedo, and which may be provided with a charge of high explosive, but which generally will be uncharged.

This surface-torpedo is constructed to tow at a predetermined lateral distance from the fore and aft line of the towing vessel, by mounting hydrovanes or planes preferably on a torpedo shaped buoyant body, in such 70 a way that the normal thrust of one set of planes tends to keep the body at a desired angle from the fore and aft line of the ship. These planes are referred to as the vertical planes the foremost of which is given a 75 greater incidence than the after or rear one. In this way longitudinal stability is obtained, and on any movement of the body away from its course, a counteracting or restoring force is set up.

Attached to the bottom of the plane is balance-weight or, if preferred, the planes may be made sufficiently heavy to form a balance weight. In this way, a buoyancy couple is obtained always tending to keep the body 85 vertical. Should the forces on the body or the waves tend to rotate the vertical plane it is obvious that an elevating or depressing force will be brought into play according to the direction of movement. If the movement 90 is an elevating one, the body will tend to be lifted out of the water, and if a depressing one, will tend to be submerged. In either case, outward thrust would be reduced and to overcome this, correcting planes are 95 mounted on the upper part of the body the thrust of which planes is in the opposite direction to that of the vertical planes.

Other planes hereinafter called horizontal planes are mounted on the body to assist the 100 buoyancy of the surface torpedo to keep it on the surface. These planes are also arranged at such angles of incidence as to introduce stability in the required directions.

In another form of construction of surface 105 torpedo the horizontal and vertical planes are combined for the purpose of utility, and this position of the fore and aft planes is so changed that they form a biplane construction in the position of the foremost plane. In 110 a body so constructed, the point of tow is so arranged that when the body is completely submerged, the dynamic reaction on this biplane unit will tend to rotate the surface torpedo so as to make the resultant dynamic 115 reaction act more in an upwardly direction than in an outwardly direction. In order to keep these planes immersed and prevent the rotatory motion being excessive and to keep the thrust outward instead of upward, the 120 point of tow of a charged torpedo is arranged at such a distance from the body that it tends to rotate the body in an opposite direction to the biplane unit. The thrusts however are so arranged that when the body is entirely submerged 125 the rotatory movement due to the biplane unit predominates.

When my invention is to be applied as a sweeping device against submarines there may conveniently be supplied to each ship 130

two charge torpedoes which are towed from the stern and arranged to go down and out relatively to the fore and aft line of the ship, with or without two surface torpedoes towed 5 from the fore part of the ship, one on either side, and carrying charge torpedoes suspended in any suitable way.

According to my invention a sweeping device as a unit consists of a charged torpedo 10 which can be fired in any one of three ways and which is towed direct from a ship or from a surface torpedo, a towing cable, which may consist of a length of electric cable, a winch fitted with a dynamometer firing gear, 15 a dropping davit by which the charge torpedo is lowered into or raised from the water, and suitable electrical apparatus comprising two sources of electric power one of high and one of low voltage, measuring instruments, switches and necessary circuit 20 connections.

The firing systems employed in a charge torpedo to fire the charge in any one of the three ways is applicable generally to all 25 towed charges and consists as follows:—

In a towed body containing a charge of high explosive a suitable striker with or without whiskers is so arranged that on being operated by meeting obstruction offering 30 the necessary resistance it closes a switch in a watertight part of the charged body.

In the towing vessel arrangements are made for either a low or a high voltage to be switched in the firing circuit.

35 In the charge body a resistance is arranged to be in parallel with the switch operated by the striker so that when the low voltage switch is closed in the ship a small current is always flowing through the detonators which are commonly used to fire the 40 high explosive. This resistance is cut out on the striker operating the switch whereby the current in the firing circuit is increased to an extent sufficient to fire the detonators.

45 In the ship one end of the electric cable from the charged body is wound around a drum provided with a suitable rubbing contact and an adjustable friction brake, and a rack which is engaged by a pawl, when the 50 charged body is being towed through the water, the pawl being held in position by a slotted bar connected to a dynamometer spring, the friction brake being released.

On the strain of the cable exceeding the 55 predetermined amount governed by the setting of the dynamometer spring, as for instance when the towing cable fouls a submerged submarine, the drum is caused to rotate against the spring, thereby rotating the 60 rack to operate the pawl and lift the slotted bar against the dynamometer spring, to operate a switch which cuts out the low voltage current and connects up a high voltage current. This high voltage current is of sufficient strength to fire the detonators in the

charged body with the resistance above referred to in the circuit.

In parallel with the dynamometer switch is a hand operated switch, which, when closed by an operator fires the detonators 70 through the resistance above referred to.

It will thus be seen that the towed charge can be fired in three independent ways (1) 75 automatically on impact (2) automatically when the strain in the towing cable exceeds a predetermined amount, and (3) at the will of an operator at any moment the towed charge is in the water.

It is desirable in all towed charges to 80 know the depth at which they are running.

This is effected according to my invention by means of a depth recording apparatus which is operated by hydrostatic pressure to adjust the value of resistance, in circuit with an ammeter provided with a dial calibrated 85 for depths in any desired unit.

In all charged bodies which when not in the water are carried by a vessel it is desirable to provide means whereby the detonators used for firing the charge of high explosive are only inserted in the firing position when the charge is actually in the water.

To effect this, I provide according to my invention, a device carrying the detonators which is operated to insert or withdraw the detonators from the charge of high explosive by the pressure due to immersion in the water whereby the charge cannot be fired unless it is actually in the water at the required depth at which the device is hydrostatically operated.

In order that the constructional details, the arrangement and operation of the component parts of apparatus according to my invention may be fully ascertained, reference 105 will now be made to Figs. 14 to 67 of the accompanying drawings.

According to my invention I construct a body 1 of a stream line form such as torpedo shaped from steel or other suitable material, 110 to the head of which a depressing plane 2 of good practical aspect ratio and efficient sectional form is attached in any suitable way such as by stays 3, and a saddle piece 4.

The following table of characteristics of a 115 4 feet and 6 inches plane having an aspect ratio 6, and of which the useful length may be taken as 3 feet 6 inches is given by way of example.

Angle of incidence of chord to horizontal.	Coefficient of lift.	Lift drift.	Center of pressure from leading edge of chord.
1 degree.....	.123	15.6	.45
3 degrees.....	.162	15.2	.42
4 degrees.....	.191	14.4	.39
5 degrees.....	.208	14.1	.37
6 degrees.....	.228	13.8	.36
7 degrees.....	.252	13.1	.35
8 degrees.....	.278	12.05	.34

The force on the plane when set at 6 degrees is as follows for the following speeds:

5	Speed in knots.	Calculated force on the plane.	Pull in towing cable from actual trial.
		Pounds.	cwt.
10		420	3
12			5
15		940	10
16			18
20		1640	22
22		2620	32
26			40
27			
28		3000	
29		3550	
15			

N. B. The pull in the cable includes the cable resistance as well as the drag of the body.

20 The body is provided with balance or ballast weights, 5, 6 the position of which relatively to the plane will depend upon the disposition of the weights of the component parts of the body.

25 By a suitable disposition of such weights the ballast weights 5, 6 may be carried by the plane by any suitable rigid but interchangeable joint. The weight 5, 6, may consist conveniently of two cylindrical bodies of different weights, one say metal, and the other of wood with a metal or other protective casing, and by being interchangeable the body can be made to run either to port or to starboard.

35 A towing cable 7, is connected to the head of the body in any suitable way, such as by shackle 8 fitting into a housing 9 provided with a cover plate 10 secured in position by screws.

40 It will be seen that the pull due to the towing cable and the thrust on the depressing plane are confined to the head portion of the body, which is preferably strengthened locally by additional plates 11, to which pad pieces for the cover plates and

45 stays are riveted.

The rear portion or tail of the body is provided with horizontal and vertical fins or planes 12, 13. An adjustable rudder 14 is pivotally mounted on the vertical fin 13 and is adjusted by rotating the screwed shaft 15, on which is mounted a nut 16, connected to a rudder by a lever 17, and bell crank 18. In addition to this adjustment a setting device is provided consisting of screwed rods 19 carried by brackets 20 and passing through holes in the rudder, which is retained in the adjusted position by nuts 21 mounted on the screwed rod on either side of the rudder.

60 A body constructed as above described can be arranged to fulfil all the conditions as hereinbefore described for towing at a predetermined depth and at a predetermined angle from the vertical at all speeds within practical limits, and have the required

stability in all directions, by the correct disposition of the metacentric height and the center of gravity, and by arranging the line of tow to pass through the center of dynamic reaction on the component parts of the body. 70

As hereinbefore described a body as above constructed may be used either as a mine sweeping or protecting appliance, or be provided with an explosive charge for use in sweeping operations against submarines, in 75 which latter case the body is referred to as a charge torpedo.

The charge torpedo consists of four separate parts, head, bonnet, body and tail.

The head in addition to the depressing 80 plane or planes has a tow anchorage as above described and is provided with a striker gear with or without suitable whiskers.

The bonnet carries a switch operated by 85 the striker, a depth indicator and a resistance for the firing circuit, together with the necessary glands and covers for keeping the parts watertight.

The body of the charge torpedo carries a 90 detonator operating gear, detonator, a primer, and a charge of high explosive.

The tail carries the horizontal and vertical planes and adjustable rudder as above described. 95

A metal bush 22 is secured in the nose of the head and is internally screw threaded for the reception of a casing 23, Figs. 17 and 18 and which is prevented from rotating by a screw 24 and in which a striker 25 is slidably, but non-rotatably, mounted. The striker rod is normally kept outward by a spring 26, and is provided with rotatable whiskers 27 on the outer end, the inner end being bored out for the reception of a spindle 28 operating a switch in the firing circuit of the detonators. At a short distance from the end of the striker rod two studs 29 and 30 are provided which are of different sizes to prevent the bonnet being put into 110 the head with this switch above referred to in the wrong relative position to the striker.

The spindle 28 passes through a watertight gland in the center of the bonnet with its axis coincident with the longitudinal axis 115 of the torpedo. At the foremost end spiral or inclined grooves 31, 32 Fig. 26 are provided of sizes corresponding to the studs on the striker rod, the studs engaging these grooves to rotate the spindle when the 120 striker rod is forced inward, a collar 33 on the switch spindle being provided to engage a stuffing box 34, forming a gland 35 for the spindle, to prevent it moving to the rear when the striker is operated. To prevent 125 any water which might leak past this gland passing on to the parts of the switch, an additional gland 36 is provided and a watertight cover 37, to form a chamber between the two glands, any water which collects in 130

this chamber being taken away by a pipe 38. An inspection door 39 is provided whereby the switch parts may be inspected and overhauled.

5 This switch consists of two spring contact arms 40, Figs. 17, 25, 26 and 54, engaging a commutator disk 41 mounted on a spindle 28, this switch being closed when the rotation of its spindle causes the contact arms 10 to break contact with the insulating portions and make contact with the conducting portions. Insulating leads from the switch are led out through a stuffing box 42, to distributing or terminal bars T, T' mounted in 15 the bonnet and provided with terminals T²⁰, T²¹, T²², T²³ and T²⁴, hereinafter referred to.

The depth indicator 43, Figs. 17, 23, 24 and 54, is secured to the bonnet and consists of a cylinder 44 in which a plunger 45 works 20 by hydrostatic pressure due to the depth of the water, which is led into the cylinder by a pipe 46. The inlet for the pipe is in the bonnet and is fitted with an adapter threaded for the reception of a pump lead by means 25 of which and a suitable air pump the depth recorder and the watertightness of the torpedo can be tested. The plunger is provided with a suitable spring 47 which is compressed when the plunger is operated due to increased 30 pressure the travel on the plunger being limited by a stop 48 engaging the rear end of the cylinder. A leak off hole is provided on the cylinder so as to drain any water away which passes the plunger to prevent it getting 35 into the electrical portion of the indicator. The rear end of the plunger rod is provided or formed with a rack like extension 49 to engage over the toothed segment 50. This rack is conveniently formed by 40 cutting a series of collars in the plunger rod, and are made circular to prevent any binding action caused by the spring trying to rotate the plunger. The toothed segment 50 carries a contact arm 51 which moves over a 45 resistance 52 consisting of a number of contact studs fixed in an insulating member with resistance coils between the studs. To the end stud an additional resistance 53 may be connected, the circuit being taken to a terminal 50 T²⁷ which is connected by a lead to a terminal T²¹, on the bar T'. The contact arm 51 is connected by a lead to a terminal T²⁸ see Fig. 54, which is connected to the terminal T²² on the bar T. The circuit is led in the 55 manner hereinafter described to an ammeter on the ship, graduated to read both amperage and depth, the resistance being so arranged that with increasing depth the resistance is gradually cut out thereby allowing an increasing current to flow.

Any other suitable form of rheostat may be used instead of the form above described.

The detonators 54, Figs. 17, 27, 28 and 54 are connected in parallel to the earth on one 65 side as illustrated in Fig. 54 and to terminals

T²³, T²⁴, on the bar T, the circuit being completed in the manner herein described.

The body of the charge torpedo is provided with stiffening rings 55, Figs. 17, 21 the front and rear rings being provided with 70 studs respectively for the reception of the head and bonnet and tail, so that the head and tail may have an adjustable setting relatively to the body. A bulkhead 56 is secured to the body and serves to support a 75 watertight casing 57 for the reception of a primer tin 58, Figs. 17 and 27, containing a suitable primer 59 for firing the high explosive 60. Enlarged detail views of the primer casing 57, primer tin 58, and primer 80 59 are clearly shown in Figs. 29 and 30. The body is also provided with buoyancy chambers 61, 62 the latter chamber being separated by a plate 63 from the chamber containing the high explosive, a plug 64 being 85 provided for inserting the same. Stops 65 are fixed on the outside of the body to keep the charged torpedo from sliding fore and aft when in the tongs of the dropping davits 90 hereinafter described. A detonator with drawing and inserting gear according to my invention is made up as a unit and is fixed in position by watertight joints and screws.

This gear consists of a casing 66 Figs. 17, 27 and 28, carrying a pivot 67 for a water-flap 68 which is forked at one end 69 to engage a pin 70 on a plunger 71 passing through a watertight gland on the foremost end of the casing. Water grooves 72 are provided on a portion of the gland extended to form a bearing for the plunger. A supporting arm 73 is secured to the top of the casing to form a bearing for the foremost end of the plunger, and carries a pivot 74 on which is mounted a lever 75, connecting the plunger to a shaft 76, secured to a sliding carrier on which the detonators are secured in any suitable way. The detonator carrier 77 is made to travel in a straight line by means of suitable guides 78 secured to the casing. These guides are rigidly secured to the primer tin so that it is not possible for the detonator to get out of line with the holes in the primer. Suitable stops are provided such as a collar 79 on the 110 plunger 71 limiting the out position and by the detonator carrier contacting with the case of the primer tin in the in position, to restrict the movement of the detonators within predetermined limits. The plunger 115 71 is made of large diameter so as to allow the hydrostatic pressure due to depth of immersion to assist the action of the water-flap.

The whole of this detonator operating 125 gear can be removed as a unit by unscrewing the casing from the body of the charged torpedo or the detonators alone can be removed by disconnecting the shaft 76 from the lever 75 and drawing the carrier 77 to 130

the rear, a joint being provided between the shaft and the carrier to allow the shaft to clear the lever.

The detonator withdrawing and inserting gear as above described may be used for any kind of weapon where it is desirable that the detonators should not be actually in the primer before the weapon is in the water.

10 The winch on which the towing cable is wound and which is applicable for use with all towed charges, consists of a drum 80 Fig. 31, to receive the towing cable, and rotating on a hollow shaft 81 carried by side-
15 plates 82 and 83, the drum being built of steel plating secured to angle sections rings or flanges and arranged low down so that the stresses on the deck due to the pull on the towing cable are reduced.

20 A brake drum 84 is bolted to the flange of the winch drum and engaged by a friction band brake 85 operated by a hand wheel 86 working on a screwed sleeve 87 for adjusting the brake. On one end of the hollow shaft 81 is mounted an indicator gear shown separately in Figs. 35 to 37, and a spur wheel 88, engaging with a pinion 89 on a shaft 90 which can be moved in or out of gear by a hand lever 91 and locked 25 in the "in" or "out" position by a locking pin 92, the shaft 90 being rotated by cranks 93 provided with handles 94, which are manually operated for winding in the towing cable.

30 The indicator gear above referred to registers the amount of towing cable which is out, and consists of two spur wheels 95, 96, the former having one more tooth than the latter the spur wheels being connected to 35 the side plates of the winch.

40 A driving pinion 97, rotating on a pin 98, is secured to the spur wheel 88, therefore for each rotation of the winch the driving pinion 97 makes a complete revolution 45 around the circumference of the spur wheels 95, 96 and in so doing drives the spur wheel 96 one tooth relatively to the spur wheel 95.

On the inner face of the spur wheel 96 a bevel wheel 99 is secured, and operates by a 50 bevel wheel 99' a shaft 100 at the upper end of which is mounted a small spur wheel 101 driving a larger spur wheel 102 provided with a pointer 103 traveling over a dial 104, graduated in suitable units to show at 55 a glance the amount of wire out.

At the opposite end of the drum to the 60 brake a pawl race 105, Figs. 31 and 33 is provided, and is engaged by a pawl lever 106 engaging in a slotted link 107 connected at its lower end to a piston rod 108 working in a cylinder containing a dynamometer spring 109. The upper end of the link is provided with a cross head 110 connected to an adjustable member 111 which controls 65 the period at which the dynamometer switch

hereinafter described is actuated. The pawl lever is put into engagement with the rack as soon as the towing cable has been paid out to what is considered to be the necessary amount, but as it may be necessary to veer 70 more cable off the winding drum after the pawl has been put into engagement, a pawl disengaging gear is fitted. This gear consists of a disengaging gear lever 112, Figs. 31, 32 and 33 mounted on one end of a pivot 75 113 the other end of which carries a crank or like member 114 provided with a pivot pin 115 for the pawl lever. When the disengaging lever is operated, the pivot of the pawl lever moves on the circumference of a circle 80 so that the pawl lever moves toward the link 107 at the same time that it moves in a downward direction to become disengaged from the rack 105. When disengaging there will 85 be a heavy strain on the towing cable as the friction brake must be put on before the disengaging lever is operated. Owing to the winch drum being locked in position with the dynamometer spring compressed to an 90 amount corresponding to the strain of the cable, the operation of the pawl lever by the disengaging lever will still further compress the spring. Owing to the friction of the pawl lever on the connecting link there will be a 95 large force tending to push the link to the rear, and to resist this tendency two curved links 116 are provided to secure the link to the side plate of the winch. To prevent excessive travel of the pawl lever thereby caus- 100 ing damage to the dynamometer switch a stud 117 is secured to the side plate of the winch and provided with a collar which limits the travel of the pawl lever to the desired amount. A hole is made in the casing 105 of the drum at one end to allow the electric towing cable 7, to pass through to the axle 81, from which it passes, as shown in Fig. 52 to the contact member or switch 118 on the winch.

110 This member consists of a contact ring 119 Figs. 52, 53 and 54 secured to but insulated from the winch shaft 81, and engaged by spring contact plungers 120, which are mounted in insulated arms 121 secured to 115 the bearings of the shaft, the plungers being duplicated for insuring efficient working. The plungers and arms are protected by watertight casings and the leads from the plungers are taken through watertight 120 glands 122, one lead being taken to terminal T¹⁵ and the other terminal T¹² in the dynamometer switch hereinafter described.

The dynamometer switch Figs. 50 and 51 consists of a pivoted arm 123 adjustably secured to the upper end of the link 107 such as by means of a screw adjustment 124, and operates a plunger 125, which normally retains a crank 126 controlled by a spring 127 which is normally under compression, the 130

movement of the crank being limited by two stops 128. The crank is rigidly connected to a drum 129 of insulating material on which three conducting metal strips 130, 131, 132 are secured and against which spring plungers 133, 134, 135, 136, 137 and 138 are arranged to make contact. Normally the strips and plungers are in such relative positions that the contact strip 132 is in contact with 5 the plungers 137 and 138. When the drum is operated through the tension in the towing cable rotating the winch drum to operate the pawl lever 106 Fig. 34, to raise the link 107 against the dynamometer spring, the contact 10 referred to above is broken and contact is made between the strip 130 and the plungers 133 and 134, and simultaneously between the strip 131 and the plungers 135 and 136. The interval of no contact is that which occurs 15 while the drum rotates through a very small angle during which the towing may elongate, the plungers 135 to 138 are mounted in or connected to terminals T^{15} , T^{14} , T^{17} , T^{16} , T^{12} and T^{25} respectively. The terminal T^{16} 20 is connected to terminal T^{19} . Fig. 54 of the winch contact, the terminal T^{14} , is connected to a terminal T^3 Figs. 46 and 54 on the firing switch hereinafter described, the terminal T^{17} is connected to a terminal T^1 of this 25 firing switch, the terminal T^{16} is connected to a conductor T^{13} which is earthed. The terminal T^{12} is connected to terminal T^{18} Fig. 30 54 of the winch contact switch and terminal T^{25} is connected to the terminal box T^x . In 35 order to determine readily whether the dynamometer switch has been tripped or not, a piece of glass is inserted in the cover of the switch directly over an indicator attached to the switch drum. This indicator 40 is marked "Ready" and "Fired" see Fig. 51, and the condition of the switch is indicated by the word which is visible. The words may be painted with luminous paint or otherwise treated so as to render them visible 45 at night.

A firing switchboard 139 Figs. 42 and 54 is mounted in a convenient position in the ship such as the forebridge and carries an ammeter 140 a push 141 for this ammeter, a 50 firing switch 142 a safety switch 143, a one pin plug and socket 144 for high voltage current or dynamo circuit a terminal box T^x , a one pin plug and socket 145 for the low voltage or battery circuit and dummy sockets 55 146 for receiving each of the pins or plugs above referred to when not in use.

The ammeter is of any type suitable for receiving small currents and is also provided with a scale graduated in depths such instrument being calibrated in conjunction with the depth indicating apparatus hereinbefore described.

The push for the ammeter consists of a spindle 147 Figs. 43 and 44 carrying a 60 contact arm 148 normally kept in position by a

spring 149 and completing the circuit between the contact springs 150, 151. Leads 152, 153, 154, 155 are led through a suitable gland, the lead 152 being taken to the terminal T^{25} Figs. 48 and 54 of the safety 70 switch, the leads 153, 154 being taken to the ammeter 140 and the lead 155 being taken to the terminal box T^x .

In the normal position the only current flowing in the ammeter circuit is that due to 75 the fall across the switch. When the push is operated the circuit between the contacts 150 and 151 is closed and the whole current flows through the ammeter. A locking clip 156 is provided to keep the push down if 80 desired. Under ordinary circumstances however, this should not be done as if the charge is fired by the battery circuit with the ammeter not shunted by the switch the moving coil of the ammeter would be burnt out. 85

The firing switch 142 Figs. 42, 45, 46 and 54 on being operated changes the sources of supply from the low voltage or battery circuit to the high voltage or dynamo circuit. This switch consists of a drum 157 of insulating material provided with contact or conducting strips, 158, 159 spring plungers 160, 161, 162, 163, 164, 165, being provided to have rubbing contact with the drum and contact strips, and being mounted in suitable guides or terminal blocks, T^1 , T^2 , T^3 , T^4 , T^5 and T^6 , the terminal T^2 is connected to terminal T^6 , terminal T^3 is connected to a terminal T^{14} , Figs. 51 and 54, in the dynamometer switch, terminal T^4 to a terminal T^{11} , terminal T^5 to the socket 190 for the battery circuit, terminal T^6 to earth and terminal T^{11} to a terminal box T^x . In the diagram of connections shown in Fig. 54 the terminal T^{11} is omitted and the terminal T^4 105 shown as directly connected to the terminal box T^x .

The contact strips 158, 159 are so arranged that the plungers 160 to 163 are off when the plungers 164 and 165 are on. The drum 157 110 is rotated by a handle 166 provided with an indicator 167, which is so arranged in conjunction with two fixed plates marked "Battery firing" and "Dynamo firing" 115 respectively, that when it partially covers the plate marked "Battery firing", the battery circuit is closed, but when it partially covers the plate marked "Dynamo firing", the dynamo circuit is closed. The normal resistance of the circuit prevents the current 120 from the battery being of sufficient strength to fire the detonators, which are fired however on changing to the dynamo circuit. The normal position of the switch is with 125 the indicator at "Battery firing".

When operating the firing switch the handle must be moved quickly, as there is a certain interval of time when no circuit is made, so that both contact firing and dynamo firing are out of action. If the towing 130

cable is being obstructed in this interval it will stretch, and if the interval is sufficiently long may even break, but by throwing over the switch quickly, the circuit will be completed before the cable would break and become earthed.

The safety switch 143 Figs. 42, 47, 48 and 54 is provided to enable the sources of electrical supply to be isolated quickly when necessary.

This switch is similar in construction to the firing switch above described and consists of a drum 168 of insulating material provided with four conducting strips 169, 15 170, 171 and 172, and engaged by spring plungers 173, 174, 175, 176, 177, 178, 179 and 180 the plungers bearing on the conducting strips when the switch is on, and the insulating material when the switch is 20 off or in the safe position.

The plungers are mounted in terminal or like blocks T^{28} , T^{29} , T^{30} , T^{31} , T^7 , T^8 , T^9 , and 25 T^{10} . The terminal T^{28} is connected to the push 141 for the ammeter 140. The terminal T^{29} is connected to the negative pole of the battery B. The terminal T^{30} is connected to the terminal T^8 in the firing switch 142. The terminal T^{31} is connected to the negative pole of the dynamo circuit D, 30 through a fuse 191, the terminal T^7 is connected to the positive pole of the battery. The terminal T^8 is connected to the plug 189 see Fig. 54, of the battery circuit, the terminal T^9 is connected to the plug 182 35 for the dynamo circuit and the terminal T^{10} , is connected to the positive pole of the dynamo circuit, through a fuse.

An indicator marked "Ready" and "Safe" 40 is attached to the drum and the switch is controlled by this indicator, suitable strips 181 being provided to limit the angular movement of the same. When the indicator shows "Safe" the sources of supply are isolated, and when showing "Ready" the 45 circuits are ready for operation.

The one pin plug and socket connection 44 for the dynamo circuit is provided to close this circuit after the charged torpedo has been dropped in the water. It consists 50 of a plug 182 Fig. 49 fitting tightly in a socket 183 when in position for use.

A lead 184 is brought from the safety switch through a holder 185 and the conductor 186 of the same is secured to the 55 plug by a screw 187. The plug is attached to the holder and a securing ring 188 keeps the holder in position.

The one pin plug and socket connection 45 for the battery circuit is similar to that 60 above described and its function is to enable the battery circuit to be closed after the torpedo has been dropped. The plug 189 and the hole in the socket 190 for this connection are smaller than the corresponding parts for the dynamo circuit, so that it is

impossible to put the dynamo connection into the battery circuit. Also if the battery connection is inserted in the socket for the dynamo connection, electrical connection between the plug and the socket will not be 70 obtained. The importance that the correct plug should enter the correct socket is very great as an error would prevent the charge being fired either by contact firing or firing at will by the operator at the switchboard. 75

The dummy sockets 146 are provided to accommodate the plugs when the torpedo is close to the ship, so as to prevent the possibility of firing.

Fuses 191 are provided to prevent damage 80 to the circuit and instruments due to the large rush of current on firing either by the dynamometer switch or by the firing switch. On firing the charge the towing cable will be broken by the explosion and a dead-short 85 circuit between the core of the cable and the earth will take place. When all the fuses are removed the circuits are fool proof.

The circuits will now be described in detail for the following four conditions, reference being made to Fig. 54.

1. Torpedo towing ready for action.
2. Torpedo firing by impact.
3. Torpedo firing at will of an operator.
4. Torpedo firing by dynamometer switch.

1. Torpedo towing ready for action.

When the torpedo is towing ready for action the circuit is led from the positive 100 pole of the battery B to the terminal T^7 in the safety switch 143 which when closed allows the current to flow through the one pin plug and socket 189, 190, to terminal T^8 in the firing switch 142, and in the normal or 105 battery firing position it flows across to terminal T^9 and then to earth. The detonators 54 being earthed and in parallel the current will flow through these to one side of the switch arm 40 in the bonnet of the charged torpedo, to the terminals T^{23} and T^{24} on the bar T then by way of terminals T^{22} and T^{26} to the contact arm 51 of the depth indicator 43, through its resistance 52 to terminal T^{27} and then to terminal T^{21} on 110 the bar T, and through the towing cable 7. This cable being connected in the manner hereinbefore described to the contact ring 119 on the winch, the current will flow from this ring to terminal T^{12} in the dynamometer switch, across the contact strip 132 to terminal T^{25} and thence to the terminal box 115 T x on the switchboard and from there to one side of the push 141. Connection is made from the other side of the ammeter 125 push to terminal T^{28} in the safety switch 143, so that the current then flows across the contact strip 169 to terminal T^{29} and so to the negative pole of the battery. The highest resistance in this circuit being the re-

120
125

sistance 52 of the depth indicator it is obviously the chief determining factor of the amount of current flowing. The deeper the charged torpedo runs the less does the resistance become and therefore the greater the current flowing in the circuit. The values are so arranged that the maximum current from the battery circuit which can flow through the detonators is insufficient to fire them when the resistance of the depth indicator is in circuit.

2. Torpedo firing by impact.

On the charge torpedo striking an object so that the striker rod 25 is forced in to operate the commutator 41 to short circuit the depth indicator resistance 52, as hereinbefore described, the current from the battery is increased to such an extent as will fire the detonators.

3. Torpedo firing at will of an operator.

When the firing switch 142 is changed to the position for "dynamo firing" the dynamo current flows from the positive pole of the dynamo circuit through the fuse 191, to terminal T^{10} , in the safety switch 143 across the strip 172 to terminal T^9 and then to the one pin plug and socket connection 181, 181 if the safety switch has been put in the "ready" position. It then flows to terminal T^1 in the firing switch then across the contact strip 158 to terminal T^8 and since this terminal together with the terminal T^6 is permanently earthed it goes to earth. The circuit from the earth through the torpedo and from there to the winch as far as the terminal box T^x is the same as above described for normal running or towing. From the terminal box the current flows through a lead to the terminal T^4 in the firing switch. The circuit is completed across the contact strip 159 to terminal T^3 then to terminal T^{30} in the safety switch 45 across the contact strip 170 to terminal T^{31} and so to the negative pole of the dynamo circuit. The depth indicator resistance again chiefly determines the value of the current flowing through the circuit.

5. Torpedo firing by dynamometer switch.

When a pull of predetermined value comes on the towing cable 7 due to it or the torpedo meeting an obstruction, the charge of the torpedo is fired automatically by the dynamometer switch throwing in the high voltage or dynamo current hereinbefore described. This current will be flowing to terminal T^1 in the firing switch as described above for firing at will. From this terminal the current will flow to terminal T^4 in the dynamometer switch, and across the contact strip 131 to terminal T^{16} and then to earth. The return circuit through the

charged torpedo will be the same as above described for normal towing. The current will flow through to the contact ring 119 and then to terminal T^{15} in the dynamometer switch, across the strip 130 to terminal T^{14} then to terminal T^3 in the firing switch 142, 70 to terminal T^{30} in the safety switch 143 across the contact strip 170 to terminal T^{31} and so to the negative pole of the dynamo circuit.

It will be seen that should an attempt be made to put the plugs 182 and 189 into the wrong sockets even though the safety switch be in the "ready" position, firing of the charge cannot occur as there is no return to the negative pole of the dynamo circuit, the contact strip in the firing switch preventing this. Also impact firing will be impossible as the positive pole of the battery would not be earthed as is necessary. As hereinbefore described the plugs are so constructed that mechanical difficulty will occur in endeavoring to insert the dynamo plug 182 in the battery socket 190.

Should there be an earth on the positive lead from the battery before reaching the safety switch and this switch be at "safe" firing of the charge will not occur even though the striker be pushed in, as the return to the negative pole is broken at the safety switch. Moreover should there be an earth on the system anywhere between the terminal box and the terminal T^{20} , and the safety switch be at "ready," it will cause a heavy current to flow which will be noted in the ammeter on depressing the push 141.

Should the positive lead from the dynamo be earthed prior to it reaching the safety switch, and this switch be at safe, firing of the charge will not occur even though the firing switch be closed, as the return to the negative pole is broken in the safety switch.

It is evident from the foregoing description of a firing system whereby a towed charge can be fired in any one of three ways, that this system can be applied to other forms of underwater charges than the charge torpedo hereinbefore described, and I desire it to be understood that this system is in no way to be regarded as being limited to the charged torpedo.

A towing cable suitable for the combined uses of towing and conveying the current consists of a conductor formed of 36 tinned copper wires No. 30, S. W. G. over which are wound tinned phosphor bronze wires 18 in number of .018 inches diameter, this giving a diameter of .123 inches to the conductor.

The conductor is insulated by one layer of pure india rubber, then one layer of vulcanized india rubber, making the diameter over the insulation .25 inches. Around this is placed a cab tire sheathing of tough rub-

ber compound which brings the diameter up to .37 inches, and over this sheathing 36 galvanized steel wires each of .028 inches diameter are wound, the diameter over the 5 armoring being .43 inches. The armoring is surrounded by a layer of well compounded bitumen tape, bringing the diameter up to .45 inches. Finally twelve strands each consisting of 7 galvanized steel wires each of .04 10 inches diameter are wound on this bitumen tape making the external diameter .68 inches. The steel armoring which is used has a breaking strain of 100 tons per square inch. The completed cable when tested on a length 15 of 100 inches broke under a load of 10.1 tons with an elongation of 4.5 per cent., the resistance of the conductor increasing by 4.22 per cent. In another form of cable the 20 central portion consists of a cotton rope, .18 inch diameter over which is wound a layer of cotton braid making the diameter on which the conductor is wound .2 inches. The conductor is braided over this cotton and consists of No. 30 S. W. G. tinned copper wire bringing the diameter up to .245 inches. The core 25 is then insulated by vulcanized india rubber bringing the diameter up to .39 inches and over this insulation a layer of cotton is braided making the diameter .415 inches. A hemp 30 braiding is now applied making the diameter .526 inches and finally the cable is armored with 20 strands each consisting of 7 galvanized steel wires each of No. 22 S. W. G. making the external diameter of the cable 35 .68. The steel armoring used in this case has a breaking strain of 120 tons per square inch. Under test the cable broke under a load of 8.55 tons with an elongation of 3.75 per cent. Before and after fracture the cable was submitted to tests both for conductor and insulation resistance and no difference in the 40 values of either of these factors, was obtained.

A davit according to my invention which 45 is used for lowering and raising the charged torpedo and which is also applicable for lowering and raising other charged bodies, consists of a jib 192 Fig. 38 built up of steel angles and cross bars hinged at its lower 50 end to a pedestal 193 which is arranged to travel on rollers 194 on a bed 195 fixed to the deck. The bed consists of two channel bars, 196 rigidly connected to cross spacing bars, and secured to the deck athwartships by 55 means of bolts, so that the davit can be run in clear of the side of the ship. At each end of the bed stops 197 are fixed to prevent the davit overrunning the bed.

The pedestal 193 consists of two vertical 60 plates 198 securely bolted to a base plate 199 which carries the rollers 194. Attached to one end of the base plate is a shaft 200 on which the jib hinges. At the upper extremity of the pedestal a bracket is secured 65 carrying a worm 201, on a shaft 202 oper-

ated by a hand wheel 203, the shaft being supported at its upper end by an arm 204 secured to the side plates of the pedestal, and rigidly secured to the jib, so that when it is rotated by the operation of the hand wheel 203 it effects the lowering or raising of the 70 jib.

The davit is run in and out by a rack and pinion gear, the rack 206 being bolted to the bed and gearing with the pinion 207 75 mounted on a shaft 208 operated by the hand wheel 209.

Clamps 210 are provided on the pedestal so as to lock the davit in any position and prevent it from moving when the ship rolls. 80

The head of the jib is provided with brackets 211 on which tongs or like members 212 are mounted on a shaft 213. The tongs shown in Figs. 39 to 41 are of metal with the gripping surface covered with leather or like 85 materials, and are constructed and operated similarly to the tongs of dropping davits used for lowering and raising charged bodies from ships in the naval service. The tongs and spreader gear for the same form no part 90 of this invention. For the purpose of clearness a short description of the gear will now be given. The upper end of each member of the tongs is extended and to one extension a spreader bar 214 is pivoted and is provided 95 with a slot to engage over a stud 215 Fig. 41 on the other extension, to keep the tongs from opening unless desired. Attached to the shaft 213 by means of a sliding sleeve 216 or the like is a bar 217 the ends of which 100 are provided with top and side wedges or like members 218, 219. The top wedges 218 are for lifting the spreader bar out of engagement with the studs 215, while the side wedges 219 are adapted to engage the extensions of the tongs and thrust them apart to open the tongs. The operating gear for the tongs consists of a hand lever 220 on a shaft 221 fixed to the jib. A further lever 222 shown dotted in Fig. 38 is mounted on 110 this shaft and is connected by a rod 223 to a lever mounted on a shaft at the head of the jib. A forked lever is attached to this shaft with the fork engaging on the sliding sleeve 216 attached to the wedge bar 217. 115

The hand lever 220 can be locked by means of a pin 224 which can be screwed into a plate 225 secured to the jib. Assuming the body is gripped by the tongs, and it is desired to drop the same, the pin 224 is removed and the lever 220 operated. This causes the forked lever to move the sleeve along the shaft 213 and carry with it the bar 217 which by means of the wedges 218, 219 cause the tongs to open. 120

Attached to the head of the jib are eye bolts 226 to which pulley blocks can be attached for hauling in the torpedo or any other body which when landed is placed in the tongs. 125

A surface torpedo according to my invention, the function of which is to tow out laterally to the fore and aft line of the vessel and travel on the surface, and support a submerged body such as the torpedo hereinbefore described, consists of a stream line or torpedo shaped buoyant body 227, Figs. 57 to 59 provided with vertical planes 228, 228', and horizontal planes 229, 229', which respectively make the body tow outward and keep the body up, the latter planes also assisting to support the charge torpedo or any other submerged body. The vertical planes 228, 228', are so arranged that the foremost plane 228 is given a greater angle of incidence than the rear one 228'. In this way longitudinal stability being obtained and on any movement of the body away from its course causing a counteracting or restoring force to be set up.

Attached to the bottom of the planes 228, 228' are balance weights 232 or if preferred the planes may be made sufficiently heavy to constitute these weights.

The point of tow on the surface torpedo is arranged low down such as by means of a bridle 230 connected in any suitable way such as by shackles 233 to the surface torpedo. The charged torpedo is towed by means of a bridle 231 attached to suitable points of the surface torpedo.

As an example of the planes used the plane 228 is arranged to have an angle of incidence of 7 degrees, and the plane 228' one degree. The useful surface of each plane being 2 feet 6 inches.

The outward thrust of the planes will vary as $K A V^2$ where K is the co-efficient of thrust, A is the area and V the velocity, for one degree K equals .123 and for 7 degrees .252.

Suppose now the surface torpedo turns 3 degrees toward the ship, the front plane is reduced to 4 degrees of incidence and the rear plane -2 degrees. From the characteristics of the plane P/V^2 for the front plane is .19 and for the rear plane nothing in this case. A large turning movement is thus set up tending to bring the axis of the torpedo back into line. Suppose the torpedo should alter 3 degrees away from the ship, then the value of K for the rear plane 228' is increased from .123 to .191 an increase of approximately 56 per cent., while with the foremost plane 228 the value of K is increased from .252 to .332 or an increase of only 32 per cent. Consequently a turning movement is set up to bring the torpedo back. It will thus be seen that this disposition of the two planes 228, 228' has the effect of introducing longitudinal stability and of always making the torpedo tend to keep in a certain direction.

The following table gives an example of the thrust on the front and on the rear plane

and also the total thrust on the surface torpedo for different speeds.

Speed in knots.	Outward thrust on front plane.	Outward thrust on rear plane.	Total thrust outward.	70
	Pounds.	Pounds.	Pounds.	
8	215	132	347	
10	324	202	531	
12	470	300	770	
14	620	410	1040	75
16	830	530	1360	
18	1050	670	1720	
20	1280	830	2160	
22	1580	1010	2590	
24	1860	1200	3060	
26	2200	1420	3620	
30	2900	1860	4760	80

The horizontal planes 229, 229' are arranged so as to give stability, the front plane in one construction being at 10 degrees incidence and the after plane at -1 degree.

The point of tow 230 is arranged well below the center of the head resistance so that the whole surface torpedo would tend to rotate clockwise by the pull of the towing member. This rotation is prevented by the pull of the charged torpedo or any other submerged body, tending to pull the head down, and by the lift of the horizontal plane 229.

If the surface of the sea was always quite smooth the surface torpedo would run quite nominally, as owing to the disposition of the plane and the points of tow it cannot deviate from its course or rotate in either direction in rough weather however the surface torpedo may be totally submerged or almost right out of the water and only running on keel.

Consider what would happen if the body is totally submerged. On the tail the curved surface 235 which has been sucking the tail down strongly is suddenly balanced by the upper curved surface 234 being immersed so that the torpedo tends to dive. This is corrected by putting a plane 237 above the after lifting plane 229' but set in the opposite direction so that when it is immersed the pull on the torpedo downward caused by the action of the tail is replaced by the depression of this plane 237. The setting of the plane 229' is adjusted by nuts 238 on 115 screwed rods 239 connected by pivots 236 to bars 240 which are pivoted to the plane, and if desired the two planes 229' and 237 can be set relatively to each other and adjusted by pivotally connecting the rods 240 120 to both of these planes.

The next change brought about is the tendency to capsise of the surface torpedo due to the water pressure on the top surface of the same. The effect of this is to incline 125 the vertical plane 228, 228' so that part of their thrust is in a downward direction and part in an outward direction. At the same time the thrust of the lifting planes 229, 229' is altered from all lift to part outward 130

thrust and part lift. The result is that the total outward thrust remains substantially the same but that of the lift is greatly reduced so that the torpedo tends to dive.

5 To overcome this tendency additional planes 241, 242, 243 are fixed on the upper part of the surface torpedo so that when these planes become immersed they act against the main planes and check the dive of the torpedo to bring it back to the surface.

10 In a modified form and one which for practical purposes is preferred, the main vertical and horizontal planes are combined 15 into resultant planes 244 and 245 Figs. 60 and 61, arranged as a biplane construction set at the desired angle to the axis of the torpedo whereby the forces on the planes can be resolved into outward thrust and 20 upward lift. With such a disposition the point of tow 246 is arranged as shown so that when the surface torpedo is completely immersed the dynamic reaction on this biplane unit will tend to rotate the torpedo so 25 as to make the resultant dynamic reaction act more in an upward direction than in an outward direction. To prevent this rotary motion becoming excessive which would result in the thrust outward being reduced, 30 the point of tow 247 of the charged torpedo is arranged at a distance from the body such as by means of the bridle 248 so that the pull due to the charged torpedo tends to rotate the body in an opposite direction to 35 the biplane unit.

40 The tail planes of the surface torpedo are similar to the planes 229' and 237, as above described, and can be provided with the adjustable setting means consisting of the nuts 238 on screwed rods 239 pivoted to bars 240 which are pivoted to the planes.

45 It is evident that the surface torpedo can be used to support any submerged body of suitable weight and buoyancy other than a charged torpedo hereinbefore described. As a further example of its use one or more surface torpedoes may be arranged in series or in pairs to support a suitable protection against torpedoes, the advantage being that 50 this protection is caused to tow with the ship substantially parallel to the fore and aft line of the ship but spaced a safe distance away, so that a torpedo is either exploded or rendered innocuous by contact 55 with this protection, and so in either case cannot effect any serious injury to the ship.

60 Figs. 62 to 67 illustrate the application of this invention for protecting ships against mines or as a mine-sweeping appliance. 65 The bodies 1' are constructed on the same principle as the charged torpedo hereinbefore described, with a main depressing plane 2, and balance weights 5, 6 and adjustable rudder 13 with tail planes as hereinbefore described, but without any internal fittings

excepting the depth indicating device should it be desired to retain this device in order to ascertain at what depth the body is running.

One or more pairs of such bodies are 70 towed from each side of the ship preferably from points well below the water line, the bodies at the bows being preferably towed from the ends of rods, submerged tubes or the like, 249 projecting outward and either 75 rigidly secured to the ship, or consisting of any adjustable member such as a plunger working in a cylinder.

Each towing cable 7' may be connected to pistons inclosed in a cylinder 250 which is 80 in communication with a pressure gage, such as by a pipe 250', mounted in any convenient part of the ship, such as the forebridge.

85 The head of the body may, if desired, be provided with a wire cutter, consisting of two converging blades, 251, 252, mounted on a block 253, rigidly secured to the head. One of the blades may be a knife-edged blade and the other a saw-blade, and the forward end of the block is suitably rounded to give a good lead to the mooring cable of a mine into the divergent opening between the cutting blades. By this means the mines are cut adrift from their moorings when engaged by the apparatus.

90 What I claim and desire to secure by Letters Patent of the United States is:—

1. A body for submergence in water to which it has relative movement, a retention line attached to said body and means provided on the body whereby the latter is deflected both sidewise and in a vertical sense so as to maintain a desired position relatively to the retention line.

2. A body of stream line form adapted to 105 be towed through water, a dynamic reaction surface arranged beneath the head of the body and so set relatively to the body as to obtain the maximum lift-drift ratio, controlling planes at the tail of said body and 110 a towing line connected to the body so that the line of tow passes through the center of dynamic reaction.

3. A body for submergence in water to which it has relative movement, having a 115 towing connection to a ship, means provided on the body whereby the latter is deflected both sidewise and in a vertical sense from the stem of the ship, so as to sweep aside moored mines from the path of the ship.

4. An apparatus for the protection of ships, comprising a pair of towed bodies for submergence in water to which they have relative movement, means provided on the bodies whereby they are deflected both sidewise and in a vertical sense and a plurality of towing lines connected to the ship so as to extend outwardly at an angle from each side of the ship.

5. A towed body for submergence in water 130

to which it has relative movement, means provided on the body whereby the latter is deflected both sidewise and in a vertical sense, a towing connection to a ship directed outwardly from the stem of said ship so as to sweep aside moored mines from the path of the ship and means provided for disconnecting the moored mine from its mooring.

6. A towed body for submergence in water to which it has relative movement, means provided on the body whereby the latter is deflected both sidewise and in a vertical sense, a towing and mine sweeping connection to a ship and a cutter mounted on the said body comprising a blade coöperation with an angularly disposed saw-edged blade, said blades being adapted to receive a cable between them and to sever said cable.

7. A towed body for submergence in water to which it has relative movement, means provided on the body whereby the latter is deflected both sidewise and in a vertical sense, provided with a towing and mine sweeping connection to a ship and with means by which the engaged mines will explode at a distance from the ship.

8. A towed body for submergence in water to which it has relative movement, means provided on the body whereby the latter is deflected both sidewise and in a vertical sense, provided with a towing and mine sweeping connection to a ship and with means by which an indication is given when a mine is engaged.

35 9. A towed body for submergence in water to which it has relative movement, means provided on the body whereby the latter is deflected both sidewise and in a vertical sense, a towing connection from the said body to a ship, a piston to which the towing connection is attached, a fluid pressure cylinder in which the piston works and a pressure gage connected to the cylinder.

10. A towed body for submergence in water to which it has relative movement, means provided on the body whereby the latter is deflected both sidewise and in a vertical sense, a towing connection from the said body to a ship, and a collapsible member carried by the towing ship adapted to project from the ship or to be collapsed at will, to which member the inner end of the towing connection is attached.

11. A towed body as claimed in claim 1, provided with an explosive charge and means for firing the said charge.

12. A towed body as claimed in claim 1, provided with an explosive charge and with means for firing the said charge on the tension in the towing member exceeding a predetermined amount.

13. A towed body as claimed in claim 1, provided with an explosive charge and with electrical means by which such charge can be exploded in the body.

14. A towed body as claimed in claim 1, provided with an explosive charge, electrical means by which such charge can be fired, and with means by which the current flowing in the electrical circuit is increased to an operative strength on the body encountering an obstruction.

15. A towed body as claimed in claim 1, provided with an explosive charge, a firing circuit, a sliding striker, a member operated by the said striker and an electrical switch device connected to said member and adapted to control the strength of the current flowing through the firing circuit.

16. A towed body as claimed in claim 1, provided with an explosive charge, means for firing the said charge under electrical control, a sliding striker, a rotary member operated by the striker, electrical switch mechanism controlled by the said rotary member, a low voltage source of current and a resistance normally in circuit with the said source, which resistance is adapted to be cut out by the said switch mechanism, whereupon the current is increased to a sufficient extent to operate the firing mechanism.

17. In apparatus as in claim 16, a depth indicating device provided in the towed body, of which device the said resistance forms a part.

18. In a towed body, a depth indicating device comprising a piston operated by hydrostatic pressure, a piston rod with rack, a toothed member engaging the rack, an electrical contact arm on the said toothed member, a resistance adapted to be adjusted by the movement of the contact arm and an electrical measuring instrument in circuit with the contact arm and the resistance.

19. In a towed body provided with an explosive charge and a detonator for firing the said charge, means for automatically moving the detonator into the firing position when the body is submerged, comprising a carrier for the detonator, a member subjected to the hydrostatic pressure of submersion and a connection between the carrier and the said member whereby the pressure of the water moves the carrier into position.

20. In a towed body provided with an explosive charge and a detonator for firing the said charge, means for inserting the detonator in the firing position when the body is submerged, comprising a pivoted member operated by hydrostatic pressure, a sliding member connected to said pivoted member and a sliding carrier on which the detonators are mounted, which carrier is pivotally connected to the sliding member.

21. In a towed body provided with an explosive charge and a detonator for firing said charge, means for inserting the detonator in the firing position when the body

- is submerged, comprising a pivoted member operated by a hydrostatic pressure, a sliding member connected to said pivoted member and a sliding carrier on which the detonators are mounted, said carrier being pivotally connected to the sliding member and means for assuring direct alinement of the detonator relative to the main explosive charge.
- 10 22. Apparatus for attacking submarines, comprising a body of stream line form provided with an explosive charge, a dynamic reaction surface extending transversely beneath the head of the said body and adapted to direct the body outwardly from the towing vessel, means for connecting a towing member to the head of the body and means for firing the explosive charge.
23. Apparatus for attacking submarines, comprising a towed body as claimed in claim 1 provided with an explosive charge and with a plurality of devices for firing the said charge adapted to fire it (a) automatically on impact with the submarine, (b) automatically on the stress in the towing member exceeding a predetermined amount or (c) at the will of an operator.
24. Apparatus for attacking submarines, comprising a towed body, provided with an explosive charge, a towing connection from said body to the towing vessel, means provided on the body whereby the latter is deflected both sidewise and in a vertical sense so as to maintain a desired position relative to the towing connection, a spring controlled switch comprising a rotating electrical circuit operating device, normally maintaining the circuit open and adapted to close the circuit against the spring pressure on the stress of the towing connection exceeding a predetermined amount, and a firing device actuated by the electrical circuit.
25. Apparatus for attacking submarines, comprising a towed body, provided with an explosive charge, a towing connection from said body to the towing vessel, means provided on the body whereby the latter is deflected both sidewise and in a vertical sense so as to maintain a desired position relative to the towing connection, a dynamometer
- 5 electrical switch gear, comprising a rotating commutator, a crank adapted to operate the commutator, a plunger connected to the crank, a pivoted arm connected to the plunger, a rod actuating the pivoted arm, a winding apparatus for the towing connection and provided with a brake, a rack carried by the winding apparatus and a pawl lever engaging the said rod and rack, for the purpose specified.
- 15 26. A towed body provided with an explosive charge, electrical means for firing the said charge, a towing line, winding mechanism on which the said line is wound, an electrical contact ring on the winding mechanism, an electrical switch controlling the charge firing means and means by which the said switch is operated to fire the charge on the strain in the towing line exceeding a predetermined amount.
- 20 27. A towed body provided with an explosive charge, electrical means for firing the said charge, a towing line, winding mechanism on which the said line is wound, an electrical contact ring on the winding mechanism, an electrical switch controlling the charge firing means, a rack device on the winding mechanism and means cooperating with the said rack by which the said switch is operated to fire the charge on the strain in the towing line exceeding a predetermined amount.
28. In apparatus as claimed in claim 26, means associated with the winding mechanism for indicating the length of towing line paid out.
- 30 29. A towed body provided with an explosive charge, electrical means for firing the said charge, a towing line, winding mechanism on which the said line is wound, an electrical contact ring on the winding mechanism, an electrical switch controlling the charge firing means, a rack device on the winding mechanism, a pawl lever adapted to engage the rack, a spring controlled slideable rod, a pivoted arm connected to the said rod, a plunger operated by the arm and an electrical switch adapted to be actuated by the plunger and to operate the electrical firing circuit.

CHARLES DENNISTON BURNEY.
